UNITED STATES PATENT OFFICE.

ROBERT MORSE WITHYCOMBE, OF SYDNEY, NEW SOUTH WALES, AUSTRALIA.

ATTACHABLE OUTER SOLE FOR BOOTS AND SHOES.

1,155,982.

Specification of Letters Patent.

Patented Oct. 5, 1915.

Application filed May 8, 1915. Serial No. 26,830.

To all whom it may concern:

Be it known that I, ROBERT MORSE WITHYCOMBE, a subject of the King of Great Britain, residing at Sydney, in the State of New 5 South Wales, Commonwealth of Australia, have invented certain new and useful Improvements in Attachable Outer Soles for Boots and Shoes, of which the following is a specification.

10 This invention relates to improvements in attachable outer soles for boots and shoes and has been devised with the main object of providing a ready attachment whereby the feet of the wearer may be maintained 15 warm.

I have observed that hospital nurses, shop assistants and others frequently have to stand for long periods on cold floors sometimes composed of bare concrete or flags 20 thereby chilling the feet and causing serious ailments and my invention is principally adapted for use in such cases.

The attachments may also be used by bowlers and others for walking on "greens" 25 or floors to prevent damage by the ordinary boots.

The invention consists of a comparatively thick layer or outer sole of felt rubber or other flexible non-conducting material, preferably resilient, provided with a metal, wood or other skeleton frame to preserve 30 its shape. The layer or outer sole piece is secured to the frame by fastenings, stitching or other means or the frame may be embedded in the sole. The frame preferably 35 has one or more stop pieces at the heel to assist in maintaining the attachment in position and straps or the like are preferably provided to readily fasten the attachment 40 to the boot. When the frame is of spring steel wire or formed of sheet metal the projections may be inclined inwardly to obtain a grip on the edges of the ordinary sole of the boot and obviate the employment of 45 straps. But in order that the invention may be more readily comprehended, I will refer to the drawings herewith, which illustrate a convenient form of attachable outer sole.

Figure 1 is a perspective view of a boot 50 having my outer sole attached thereto. Fig. 2 is a perspective view of the outer sole partly in section. Fig. 3 is a transverse section through an outer sole showing method of inserting and securing the frame therein.

Like reference characters denote similar 55 like parts throughout the specification and drawings.

5 is a boot to which the outer sole 6 is attached by means of the toe strap 7 and heel strap 8. These straps may be of elastic webbing and are secured to the projections or loops 9 formed on the wire frame 10. This frame 10 is preferably inserted or embedded in the sole 6 in a slit as at 11 and the edges of which are stitched as at 12. 65 The outer sole may be of thick felt rubber or other flexible material possessing some resiliency.

The straps 7 and 8 may end in a hook 13 for fastening to one of the loops 9 as shown. 70 When the frame is of wire or sheet metal it may be shaped to conform with the tread or surface of the ordinary sole of the boot, and, as here shown, when of spring wire the projections or loops may normally be inclined inwardly to grip the edge of the sole 75 in addition to the securing straps 7 and 8.

The attachment, herein described, is light, noiseless in use, practically unobservable and have the effect of increasing the height 80 of the wearer.

Having thus described my invention what I claim as new and desire to protect by Letters Patent is:—

1. A detachable outer sole for shoes comprising, a sole piece of flexible material being formed with a slit in the edge thereof, a reinforcing member arranged in said slit and co-extensive therewith, and means for securing said sole piece to the sole of 90 the shoe.

2. A detachable outer sole for shoes comprising, a sole piece of flexible material, a continuous reinforcing member embedded in the edge of said sole, loop portions 95 formed in said reinforcing member and projecting beyond the edge of said sole, and means co-operating with said loop portions for securing said outer sole to the sole of the shoe.

3. A detachable outer sole for shoes comprising, a sole of flexible material having a marginal slit, a wire frame inserted in said slit in the sole and fastened therein, and means for attaching the outer sole to the 105 shoe.

4. A detachable outer sole for shoes comprising a piece of flexible material adapted

to be applied to the bottom of a shoe to provide the outer sole, said outer sole being formed with an inwardly extending peripheral slit, a resilient reinforcing wire introduced in said slit and co-extensive therewith, loop portions formed in said wire and extending beyond the peripheral edge of said outer sole and adapted to engage with said shoe, and means for securing the 10 portions of the bifurcated edge of the sole

together, thereby embedding and securing said wire therebetween.

In testimony whereof I have hereunto set my hand in presence of two subscribing witnesses.

ROBERT MORSE WITHYCOMBE.
